G. MELLEN.
CRUCIBLE FURNACE.
APPLICATION FILED FEB. 23, 1911.

Patented Dec. 15, 1914.

Fig. 2.

UNITED STATES PATENT OFFICE.

GRENVILLE MELLEN, OF MOUNT VERNON, NEW YORK.

CRUCIBLE-FURNACE.

1,120,732.

Specification of Letters Patent. Patented Dec. 15, 1914.

Application filed February 23, 1911. Serial No. 610,443.

To all whom it may concern:

Be it known that I, GRENVILLE MELLEN, a citizen of the United States, and resident of Mount Vernon, in the county of Westchester and State of New York, have invented a certain new and useful Crucible-Furnace, of which the following is a specification.

This invention has for its object to provide a furnace adapted to general use, largely applicable to melting metals, particularly adapted to the melting of "scrap" metal, such as "clippings", "turnings", "filings", etc., which are to be converted into ingots for the trade, especial use being the melting of aluminum "scraps" which has heretofore been done at a loss of from ten to forty per cent. owing to the conversion into oxid, and which can be melted in my present furnace with the loss reduced to between one half and five per cent.

A further object of this invention is to provide a furnace in which metal can be melted or material treated by heat in the atmosphere of a partial vacuum which enables the withdrawal of gases arising from the material being treated, and, in the case of the melting of metals, which shall do much to obviate the injurious effects which arise from the occlusion of gas.

With these and other objects in view, I have devised the novel furnace which I will now describe, referring to the accompanying drawings forming a part of this specification, and using reference characters to indicate the several parts thereof, wherein,

Figure 1. is a sectional elevation of a furnace embodying my invention; Fig. 2. is a sectional plan view on line 2, 2, in Fig. 1, looking in the directions of the arrows.

Similar numerals of reference indicate corresponding parts in the two views.

The numeral 1 indicates the interior of a treating or melting chamber.

43 1^a indicates a chamber adapted to contain the material to be treated, and made of such material as fire clay, or the like, and is, or acts in the capacity of, a crucible. Said chamber, 1^a, is shown inclosed within an airtight shell or chamber, 2, which I have shown enveloping and tightly fitting against the chamber or crucible, 1^a.

45 4, indicates a circular insulating disk or cap of any suitable material, such as asbestos or the like fitting evenly on the upper face of the wall of the crucible, 1^a, and

fitting closely against the inner side of the wall of the airtight shell or chamber, 2, and substantially spaced from the cover, 3.

Upon the furnace parts so far described I provide a suitable lid or cover, 3, said lid or cover fitting substantially airtight upon the shell or chamber, 2, by any suitable means. Lid or cover, 3, is shown provided with a flange having threads receiving corresponding threads on the rim of shell, 2. Chamber 1 is connected with suitable means for producing and maintaining a partial vacuum therein. For this purpose any suitable means may be provided. I have shown 60 vacuum pipe, 14^b, connected by union, 14^a, with the nipple, 14^c, on cover, 3, communicating with an opening, 14, in the cover, 3. I have also shown cover, 3, provided with a peep-hole, 13. In order to render peep-hole, 65 13, airtight it is provided with a piece of glass, 13^a, shown held in place by washer, 13^b, and a sight-tube, 13^c, threaded as indicated by 13^c, into a suitable opening in cover, 3. Both space, 4^a, and insulating cover, 4, 70 serve to somewhat insulate the main cover, 3, from the direct action of the heat.

75 Numeral 5, indicates a wall of refractory material which surrounds and tightly fits against the airtight shell, 2, and serves to 80 protect shell, 2, from the direct action of the flame.

85 6 indicates the combustion chamber.

90 6^a, indicates the channels which pass up through the base-plate, 11, and through the refractory base-wall, 12^a, into the combustion chamber, 6, and which serve to admit the air from without so as to allow circulation within the combustion chamber, 6.

95 6^b indicates the channels which pass through the refractory wall or covering, 12, and through the incasing metal sheet, 8, and which serve to allow the exit of the products of combustion. These channels, 6^b, are connected with any suitable form of a flue. 100

11^a indicates the feet or supports which are attached to the base-plate, 11, upon which the furnace rests.

105 10 indicates the top-plate which is similar in form to a washer and which rests upon the upper surface of the refractory wall, 12, and metal casing, 8.

110 9 indicates the bolts which bind the top-plate, 10, to the base-plate, 11, and which serve to hold the furnace parts in their proper position.

12 indicates the surrounding or contain-

ing wall which incloses the vital parts of the furnace. Said refractory wall, 12, is shown fitting tightly against the airtight shell, 2, thus serving to aid the support of the said airtight shell, 2, and thus also does much to insulate the outward upward radiation of heat.

9^a indicates the nut at the end of the bolt, 9.

10 3^b indicates the handles which are attached to the cover, 3, and by which said cover, 3, is engaged for the purpose of removing or placing it upon the rim of the shell, 2.

15 7^a indicates the channels which pass through the refractory wall, 12, and which serve to conduct the fuel into the combustion chamber, 6.

20 7 indicates the continuation of the fuel pipe, and communicates through part of the wall, 12, with the channel, 7^a.

7^b indicates the continuation of the air-pipe which connects with the fuel pipe, 7, at 7^c.

25 To reduce or melt the material in the furnace the cover, 3, is removed, the crucible containing the material may be lowered into the chamber, 1, but owing to the fact of the prolonged life of the crucible, in practice the 30 material is charged into the crucible after the latter is placed in chamber, 1, fitting tightly into the airtight shell or chamber-wall, 2, and the lid replaced substantially airtight upon the rim of the shell or chamber, 2. The

35 vacuum is established within the melting chamber, 1, and maintained therein if desired. At this stage, if required, any gas may be admitted into the said chamber, 1 through pipe 14^b, by operating suitable

40 valves connecting a vacuum pump and supply of compressed gas, not shown, the gas being maintained therein if desired. Also if preferred any gas may be compressed therein and the pressure substantially maintained. In this way the material to be treated is heated in the atmosphere of a partial vacuum or in the atmosphere of any gas either under normal or increased pressure, as may be required. The material is

placed in the furnace melting chamber, the 50 desired atmosphere established and maintained, the fuel ignited, the combustion maintained and regulated to create such heat as may be required to cause the reduction or melting of the material. 55

Having thus described my invention, I claim:

1. A furnace comprising a crucible, a gas-tight shell, surrounding the bottom and sides of the crucible, a cover screwed on to 60 said shell, said cover having connected thereto a conduit through which gas may be introduced or withdrawn, and a refractory covering for the gas-tight shell.

2. A furnace comprising a crucible, a gas-tight shell, surrounding the bottom and sides of the crucible, a cover screwed on to said shell, said cover having connected thereto a conduit through which gas may be introduced or withdrawn, a refractory 70 covering for the gas-tight shell, and an inclosed combustion chamber surrounding the lower portion of said gas-tight shell and crucible and separated therefrom by a wall of refractory material. 75

3. A furnace comprising a crucible, a gas-tight shell, surrounding the bottom and sides of the crucible, a cover screwed on to said shell, said cover having connected thereto a conduit through which gas may be introduced or withdrawn, a lid for said crucible, spaced from said cover, and a refractory covering for the gas-tight shell. 80

4. A furnace comprising a crucible, a gas-tight shell, surrounding the bottom and sides of the crucible, a cover screwed on to said shell, said cover having connected thereto a conduit through which gas may be introduced or withdrawn, handles attached to said cover, and a refractory covering for the 90 gas-tight shell.

Signed at New York in the county of New York and State of New York this 11th day of February A. D. 1911.

GRENVILLE MELLEN.
